UNITED STATES PATENT OFFICE.

GEORGE J. MUCHER, OF TROY, NEW YORK.

RESISTANCE.

Application filed November 30, 1927. Serial No. 238,801.

This invention relates to resistances, and has for an object to provide an improved construction over my prior application, Serial No. 134,042, wherein one or a large number of compression members may be arranged in a single housing.

Another object of the invention is to provide a resistance which is very sensitive and accurate, and which may be readily adjusted to vary the action of the resistance element, whereby the device may be used with current rectifying devices, telephone stabilizing devices, and also for other electrical uses where maximum efficiency and balancing adjustments are required.

A still further object is to provide an improved resistance, wherein a multiple of resistance units are provided with independent adjustment for each unit.

A still further object, more specifically, is to provide a resistance unit wherein the means for adjusting the compressing unit is associated with a spring structure which maintains a constant contact, notwithstanding the varying pressures provided, or notwithstanding the reversing of movement of any of the members.

In the accompanying drawing—

Figure 1 is a longitudinal vertical sectional view through a resistance structure disclosing an embodiment of the invention.

Figure 2 is a sectional view through Figure 1, approximately on line 2—2.

Figure 3 is a view similar to Figure 2 but showing a large number of individual units in a single casing.

Figure 4 is a plan view of a spring plate used in connection with the structure shown in Figures 1, 2 and 3.

Referring to the accompanying drawing by numerals, 1 indicates a casing, which in the present instance, is formed of metal, but if desired, could be formed of insulating material or other material, without departing from the spirit of the invention. Where the casing 1 is made from insulating material, the compression screws 2 and 3 become terminals instead of the terminals 4 and 5. The terminals 4 and 5 are what may be termed, common return terminals, so that one or more may be used as desired. As indicated in Figure 1, these terminals are in frictional engagement with the offset portions 6 and 7 of casing 1. Where the casing 1 is metal, a good contact is not secured. In forming the offsets 6 and 7, corresponding depressions are

formed interiorly of the casing 1, and in these depressions insulating plates 8 and 9 are provided, said plates preferably filling the depressions. Rivets or other metallic connecting means 10 and 11 are provided, said rivets having comparatively large heads 12 and 13 so as to present an ample surface to the resistance bodies 14 and 15. Arranged exteriorly of the contacts 4 and 5, are insulating plates 16 and 17, and arranged exteriorly of these are the individual contacts 18 and 19. The rivets 10 and 11 act to clamp the respective contacts in place as shown in Figure 1, and also clamp the plates 8 and 9 in position, whereby the heads 12 and 13 are automatically held in the desired position, while the bodies of the rivets are out of contact with the depressed portions 6 and 7, as there is a large opening in these depressed portions. As the plates 8 and 9 contact tightly with the bodies of the rivets 10 and 11, these rivets are held centrally of the respective apertures in the depressed portions 6 and 7, thus the plates 8 and 9 act in the double capacity of insulating means for insulating the heads 12 and 13 from the depressed portions 6 and 7, and as means for centering the pins in the openings in the depressed portions. The depressed portions and plates 8 and 9 may be made of any desired size, but preferably approximately the proportion shown in Figure 1 is the desirable size so that current passing into the casing 1 will have to pass through an appreciable part of the resistance material 14 and 15 before it can reach the enlargements 12 and 13. The resistance material 14 and 15 may be any desired kind of resistance material, as for instance, metal finely divided, carbon or other conducting material mixed with mica finely divided, or other material which will give a resilient action to the body.

The structure in Figure 1 is substantially elliptical as illustrated in Figure 2, and is divided by a wall 20 which may be metal or insulating material as desired. This wall divides the casing 1 into compartments or sections 21 and 22, the respective sections being identical. In use, preferably either of the terminals 4 or 5 are used, but not both, while current is taken off both the terminals 18 and 19. Also, if desired, the density of the resistance material 14 may be different from the resistance material 15, whereby the current taken off the terminals 18 and 19 will be adjusted to the demand of the individual in-

strument to which it is electrically connected. Arranged in each of the sections 21 and 22, is a compressor 23. As the respective compressors and associated parts are identical, the description of one will apply to both. The compressor 23 is preferably formed with a central body 24 of felt or some other resilient material, and on the lower face of the body 24 is a plate 25 of metal, while on the upper face a similar plate 26 is placed. Plate 26, however, is preferably provided with pressed out tongues 27 which extend through the body 24 and plate 25 so as to be bent over or upset and act as rivets for holding the two plates in position and in firm contact with the body 24. If desired, separate rivets could be used instead of tongues 27 or even bolts or other forms of clamping means. Plate 26 is provided with a raised portion 28 which is formed with a narrow slot or opening 29 merging into a large opening 30. The large opening 30 is adapted to accommodate the head 31 connected with the neck 32 extending from the clamping screw 2. The neck 32 is substantially the same length as the thickness of plate 26, though if desired, it may be made slightly longer. In securing the parts together, the screw member 2 is positioned so that the head 31 may be forced through the opening 30 and then moved over until neck 32 is fitting in the slot 29. If the parts are absolutely accurate, head 31 or some part of the screw 2 will always remain in contact with the plate 26. However, quite often when manufacturing the devices, the absolute accuracy desired is not secured, and to compensate for this, a spring plate 33 (Figure 4) is inserted beneath the plate 26 and pressed or embedded in the body 24. The plate 33 is shown substantially triangle, and provided with a notch 34 in each corner for accommodating the three rivets 27. However, if four rivets are used, two notches 34 would be sufficient, whereas if the rivets 27 were differently arranged, the notches 34 would be arranged accordingly. By using the notches 34, plate 33 is prevented from becoming displaced and, consequently, the bent up tongue 35 is always resiliently pressing against the head 31 even though this part of the device may be loosely connected with plate 26. By reason of the tongue 35, a good electrical contact is always maintained as the screw 2 is forced inwardly or outwardly. From Figure 1 it will be noted that the screw 2 is threaded through an internally and externally threaded sleeve 36 which is screwed into a cover plate 37 formed

with its edges fitting tightly into the turned over bead 38 forming the upper edge of the casing 1.

In Figure 3, a large number of independent sections 21' are provided, and all these sections may be connected to a common return or supply, while each section has an individual outlet. In this way, any one of the compression screws may be tightened and the outlet from that section will be varied accordingly. If there should be six compartments or sections 21', the various compression screws 70 could be adjusted so that six different resisting units would be presented.

What I claim is:

1. In a resistance unit, a resistance body, a casing containing said body, a contact carried by said casing at one point, a compressor carried by said body, said compressor having a top plate formed with an opening having a large portion merging into a restricted portion, threaded means for shifting said compressor back and forth, said threaded means being provided with a head fitted between said plate and with a neck fitted in said restricted portion of said opening, said head being of a size to pass through said opening 85 at said large portion and a spring plate arranged beneath said first mentioned plate with a resilient tongue continually pressing said head.

2. In a resistance unit, a compressor 90 formed with a fibrous body and a metallic plate on each face thereof, means for connecting said plates together and an actuating member having one end rotatably connected with one of said plates, and a spring 95 plate arranged beneath one of said plates and against said fibrous body, said spring plate having a portion continually pressing against said actuating member.

3. In a resistance unit, a compressor comprising a fibrous body, a metal plate on each face of said body, means for connecting said plates together, said plates being of less diameter than said fibrous body, one of said plates having an opening for receiving an 105 actuating member, and a contact plate arranged beneath the plate having the opening, said contact plate being continually in contact with the plate having the opening and formed with means extending across said 110 opening so as to continually engage the actuating member when the device is in use.

Signed at Troy in the county of Rensselaer and State of New York this 21 day of Nov. A. D. 1927.

GEORGE J. MUCHER.

DISCLAIMER

1,701,386.—*George J. Mucher*, Troy, N. Y. **RESISTANCE**. Patent dated February 5, 1929. Disclaimer filed July 31, 1930, by the patentee.

Hereby enters this disclaimer of claims 2 and 3 in said specification which is in the following words, to wit:

“2. In a resistance unit, a compressor formed with a fibrous body and a metallic plate on each face thereof, means for connecting said plates together and an actuating member having one end rotatably connected with one of said plates, and a spring plate arranged beneath one of said plates and against said fibrous body, said spring plate having a portion continually pressing against said actuating member.

“3. In a resistance unit, a compressor comprising a fibrous body, a metal plate on each face of said body, means for connecting said plates together, said plates being of less diameter than said fibrous body, one of said plates having an opening for receiving an actuating member, and a contact plate arranged beneath the plate having the opening, said contact plate being continually in contact with the plate having the opening and formed with means extending across said opening so as to continually engage the actuating member when the device is in use.”
